UNITED STATES PATENT OFFICE

JOHN B. STEEL, OF NORFOLK, VIRGINIA, ASSIGNOR TO FARMERS MANUFACTURING COMPANY, OF NORFOLK, VIRGINIA, A CORPORATION OF VIRGINIA

SHIPPING BASKET

Application filed November 24, 1931. Serial No. 577,077.

This invention has relation to that type of shipping basket or hamper used for the shipment of fruits and vegetables and generally constructed of thin veneer staves suitably fastened together by hoops and provided with a substantially solid bottom, the upper end of the basket being provided with wire handles which serve during shipment for fastening the cover in place. The object of the present invention is to simplify and improve the bottom construction to the end that it will be exceptionally sturdy so as to withstand the roughest usage in handling when the basket is loaded and which will be comparatively inexpensive to manufacture, as more fully hereinafter set forth.

In the drawing annexed, Fig. 1 is a side elevation of my improved basket.

Fig. 2 is a vertical sectional view taken through the lower part of the basket;

Fig. 3 is a bottom view of the basket partly in horizontal section; and

Fig. 4 is a top view of the bottom plate detached.

In the drawing, the reference numeral 5 designates the veneer staves which are bound together at the lower ends of the basket between a pair of hoops, an inner hoop 6 and an outer hoop 7, staples being usually used for this purpose. In the basket thus formed, I fasten my improved bottom, which consists of a plurality of thin boards 8, preferably fastened together edge to edge by means of the usual sheet metal fasteners 9.

Fastened to the underside of the bottom 8 is a series of bars 10, spaced apart equidistantly around the circular edge of the bottom and set back from the edge a distance equal to the thickness of the hoop 6. These bars have their inner faces straight and their outer faces curved to fit snugly against the inner wall of the hoop and each is nailed to the bottom 8 by a plurality of nails 11 driven down through the bottom boards and terminating in the bar 10. When the bottom thus formed is placed in the basket, with the segmental bars 10 facing downwardly, the curved outer faces of these bars 10 fit against the inner face of the inner hoop 6 and the

top of said hoop. To secure the parts in this assembled relationship, I drive two or more nails or staples 12 into the bars 10 through the lower hoop structure 6, 7, the ends of the nails terminating in the bars 10. At least two of the bars 10 are arranged to span the joint or joints formed by making the bottom 8 of two or more pieces of board, which is the usual practice.

The bottom structure such as described has been found in practice to be very sturdy and thus well adapted to withstand the rough handling these baskets receive on the way from the packer to the consumer. This sturdy structure permits the bottom proper to be made of thinner and cheaper lumber than ordinarily used. It will be observed also that as compared with that type of solid bottom which is provided with a cleat or slat fastened to its underside and abutting against the inner hoop, my bottom has the advantage that it does not obstruct to any material extent the space created under the basket by the raised bottom, this being important in that it not only permits the basket to be stacked on another basket whose top is bulged upwardly by the contents thereof, but also because it renders it easier to find a place on the floor or the ground on which to place the basket in a steady, upright position. Also as compared with the aforesaid cross-bar type of bottom, I not only obtain a sturdier construction by reason of the fact that the segmental bars 10 are placed at four different points around the bottom, but also I economize in the use of lumber in view of the fact that I may use for the bars 10 small scraps of lumber which have heretofore been unusable.

My device possesses the further advantage against the cross-bar type of bottom because in that type of bottom the ends of the bar abut against the hoop and therefore the fastening nails have to be driven into the ends of the bar, i. e. parallel with the grain of the wood, whereas in my structure the nails are driven cross-grain into the segmental bars, thus giving me a nail anchorage much safer and stronger than is possible with the bar or cleat type of bottom and at the same time making it unlikely that rough usage of the

basket when loaded will dislodge the segmental bars.

I claim:

- 5 In a shipping basket of the type set forth,
a body structure having the lower ends of the
staves thereof clamped between a pair of
bottom hoops, one inside the body and the
other outside thereof, a board bottom whose
outer edge rests on the upper edge of the
10 inner hoop, and a plurality of narrow bars
fastened to the under-face of the bottom and
having their outer edges curved to fit against
the inner face of the hoop, the grain in each
one of these bars running lengthwise thereof
15 and each bar having its outer face curved
to fit against the inner face of the hoop,
whereby the center portion of the bottom is
left unobstructed, said bars being spaced
apart around the hoop structure and being
20 directly fastened to the hoop structure by
fastenings passing inwardly through the
hoop structure and entering said bars across
the grain thereof.

In testimony whereof I hereunto affix my
25 signature.

JOHN B. STEEL.
